UNITED STATES PATENT OFFICE.

MAURICE H. STANLEY, OF NEW YORK, N. Y.

GAME.

Application filed August 15, 1921. Serial No. 492,234.

To all whom it may concern:

Be it known that I, MAURICE H. STANLEY, a citizen of the United States of America, residing at New York, N. Y., have invented 5 a new and useful Game, of which the following is a specification.

This invention relates to a new and improved game to be played with cards, the object being to provide a game to afford entertainment and amusement, particularly to 10 children and younger people, in that no high degree of skill is required.

In the accompanying drawing:

Figure 1 is a plan view of one of the 15 cards;

Fig. 2 is a plan view of another card;

Fig. 3 is a plan view of another card; while

Fig. 4 is a plan view of still another 20 card.

It should be understood that in the accompanying drawings I have shown only four cards of a full deck of conventional playing cards, having the usual designations 25 for the four suits the cards shown being the joker, an ace, an eight-spot and a deuce. Upon the joker is a secondary legend announcing that the one to whom the joker is dealt shall take all of the tokens or counters 30 in the center of the table, plus a certain number in addition from each player. In this particular instance the legend reads, "Take all and collect 5 from each player." The legend on the ace is, "Take all," indicating 35 that the one to whom the ace is dealt shall take all the tokens then in the center of the table. The legend on the eight-spot is "All put 1," indicating that whenever an eight-spot is dealt all the players will put 1 40 token in the center of the table. On the deuce the legend reads, "Put 5," indicating that the one to whom the deuce is dealt will put 5 tokens in the center of the table.

A regular deck of playing cards is used, 45 which, as is well known, have values running from the joker down to the deuce, the joker being of the highest value. So in the present game. The legends on the cards of different denominations have a plus and 50 minus value corresponding respectively thereto, that is to say, the joker has the greatest value, as it gives to the holder all tokens in the center of the table, plus 5 from each player. The holder of the ace 55 takes all the tokens in the center of the table. The holder of a king takes 5 tokens

from the center of the table; the holder of the queen 4; the jack 3; the ten-spot 2; the nine-spot 1. The eight-spot and the seven-spot are preferably blanks, or, as indicated 60 above, may bear a secondary legend directing all players to put 1 token in the center of the table. The holder of the six-spot is required to put 1 in the center of the table; the holder of the five-spot 2; the four-spot 3; the three-spot 4 and the deuce 5.

In beginning the game, each player is given a corresponding number of tokens or counters of any sort. The cards are then shuffled and dealt one by one to the several 70 players. As the game progresses one player after another will be eliminated, until finally, when all of the tokens have been gained by one player, the game is over.

The particular legends employed on the 75 particular cards may be varied at will, it being important only to have the respective legendary values correspond to the values of the respective playing cards of each suit, so that whenever a player gets a card above 80 an eight-spot for example he knows, even without reading the legend, that he is to receive a token from the center of the table. On the other hand, a player receiving any card below the seven-spot, knows that he is 85 called upon to put tokens into the center of the table.

In the claim I shall refer to the deck of cards as a deck of conventional playing cards, it being understood that I have in 90 mind an ordinary playing card deck. I shall also designate the additional legends thereon as secondary legends. Manifestly, such a deck of cards may be used for playing any of the regular card games, as well 95 as the special game described herein.

What I claim is

A deck of conventional playing cards, said cards bearing thereon secondary legends 100 designating values other than those represented by the regulation suit designations on said playing cards, the secondary legends corresponding relatively in value to the value of the cards of different denominations in each suit respectively, those secondary legends on the cards above one of the cards of medium value designating a progressively increasing plus value, respectively, while those legends on the cards below said card of medium value designate a progressively 105 increasing minus value, respectively.

MAURICE H. STANLEY.
